(57) **CLAIM**

We claim a new ornamental design for an insert for footwear, as shown and described.

DESCRIPTION

FIG. 1 is a front elevational view of an insert according to a first preferred embodiment of our new design;

FIG. 2 is a bottom plan view of the insert of FIG. 1;

FIG. 3 is a left side elevational view of the insert of FIG. 1;

FIG. 4 is a rear elevational view of the insert of FIG. 1;

FIG. 5 is a top plan view of the insert of FIG. 1;

FIG. 6 is a right side elevational view of the insert of FIG. 1;

FIG. 7 is a front elevational view of an insert according to a second preferred embodiment of our new design;

FIG. 8 is a bottom plan view of the insert of FIG. 7;

FIG. 9 is a right side elevational view of the insert of FIG. 7;

FIG. 10 is a rear elevational view of the insert of FIG. 7;

FIG. 11 is a top plan view of the insert of FIG. 7; and,

FIG. 12 is a left side elevational view of the insert of FIG. 7.
